POWER TRANSMISSION

Harry F. Vickers, Detroit, Mich., assignor to Vickers Incorporated, Detroit, Mich., a corporation of Michigan

Application January 26, 1940, Serial No. 315,691

9 Claims. (Cl. 103—45)

This invention relates to power transmissions, particularly to those of the type comprising two or more fluid pressure energy translating devices one of which may function as a pump and another as a fluid motor.

The invention is particularly concerned with power transmission systems adapted for pumping oil wells. Pump jacks for oil wells in use at the present time are of various types, one such type which is coming into wider use being the hydraulically actuated type wherein a cylinder and piston hydraulic motor situated directly over the well is utilized to actuate the sucker rods of the well pump. Pump jacks of this character frequently utilize a separate hydraulic cylinder and piston forming a counterbalance reducing the power required to operate the pumping unit.

Many oil wells yield oil which is mixed with a considerable portion of water, and where the yield is of this character it is customary to provide a settling tank into which the mixed oil and water is passed and where the water settles to the bottom leaving the oil to be collected from the top. Certain wells are so situated on the ground surface that it becomes impossible to drain the waste water or tailings by gravity, and it is accordingly necessary to provide a tail pump for elevating the separated water to a point where it may be drained away naturally.

It is an object of the present invention to provide an improved oil well pumping unit incorporating a tail pump which may be readily operated from a hydraulic type of well pumping unit.

Further objects and advantages of the present invention will be apparent from the following description, reference being had to the accompanying drawing wherein a preferred form of the present invention is clearly shown.

In the drawing:

Figure 1 is a diagrammatic view partly in section of a well pumping unit embodying a preferred form of the present invention.

Figure 2 is a fragmentary cross section taken on line 2—2 of Figure 1.

Referring now to Figure 1, there is illustrated a work cylinder 10 which is mounted vertically over the casing head 12 of an oil well, the casing of which is designated as 14. The work cylinder 10 has end castings 16 and 18 through which suitable connections 20 and 22 are provided. A piston 24 is reciprocably mounted in the work cylinder 10 and has a rod 26 which is connected to the sucker rods in the well. Mounted upon a suitable box-like framework 28 is a counterbalance cylinder 30 having end castings 32 and 34 in

which suitable connections 36 and 38 are provided. The counterbalance cylinder 30 has a piston 40 the rod 42 of which projects through the end casting 32 by means of a stuffing box 5 and carries a counterbalance weight 44.

The work and counterbalance cylinders are connected together by a hydraulic circuit which includes a pressure fluid pumping unit 46. Thus the unit 46 is connected by a pipe 48 to the connection 22 of the work cylinder 10 and by a pipe 50 to the connection 38 of the counterbalance cylinder 30. Preferably the lower ends of the cylinders 10 and 30 are connected together by a pipe 52 in which is incorporated a tail pump operating cylinder, later to be described. The pump unit 46 may be of any suitable construction operative to alternately deliver fluid in one direction or the other between pipes 48 and 50.

A suitable automatic reversing mechanism is provided comprising a pair of levers 56 and 58 pivotally mounted in the end castings 32 and 34 and adapted to be actuated alternately by contact with the beveled ends of the piston 40 at the limits of its stroke. The levers 56 and 58 may be connected together by a link 60, and by means of linkage 62, crank shaft 64 and link 66 may be connected to actuate the reversing lever 68 provided at the pump unit 46. Also a pair of levers 71 and 73 are provided at the work cylinder 10 and connected together by a link 74 and connected by a link 76 to a reverse lever 77 at the pump unit 46. The latter unit includes means, not shown, for synchronizing the two pistons 24 and 40 whenever they get out of time by a predetermined amount due to leakage losses from the pipe 52. Such mechanism acts to replenish the secondary circuit connecting the lower ends of the cylinders through a replenishing pipe 79. The pump unit may also be provided with a starting and stopping control handle 70. The mechanism thus far described forms per se no part of the present invention and is intended merely as a typical hydraulic well pumping unit to which the present invention is applicable.

For further details of construction of a pumping unit of this character reference may be had to the copending applications of Harry F. Vickers and Kenneth R. Herman, Serial No. 281,926, filed June 29, 1939, for Oil well pumping machinery, and of Harry F. Vickers, Kenneth R. Herman and Jesse Moser, Serial No. 313,862, filed January 15, 1940, for Oil well pumping apparatus.

For the purpose of elevating the separated water a tail pump generally designated 72 is provided. The tail pump 72 comprises a cylinder 76

in which a piston 18 is reciprocably mounted. The latter has an operating rod 80. The cylinder 76 has a head casting 82 communicating with the space to the left of the piston 18 and containing the customary inlet connection 84 and outlet connection 86 in which check valves 88 and 90 are located respectively.

For the purpose of operating the tail pump 72 there is provided in the pipe 52 an operating cylinder 92 having a piston 94 connected to the rod 80 of the tail pump. The cylinder 92 has its two ends connected between the two portions of pipe 52. At each end of the cylinder 92 there are provided auxiliary ports 96 and 98 which communicate by means of check valves 100 and 102 with ports 104 and 106 located in the side walls of the cylinder 92. The latter ports are spaced from the ends of the cylinder by a distance somewhat greater than the length of the piston 94. Preferably a bypass pipe 108 is connected across the ends of the cylinder 92 and provided with a manually operable shut-off cock 110.

In operation with the pumping unit 46 running and the starting handle 70 shifted to running position, the pumping unit withdraws power transmission oil from the top of the work cylinder 10 through connection 22 and pipe 48 and delivers it through pipe 50 and connection 38 to the upper end of counterbalance cylinder 30. The piston 24 and the sucker rods in the well are accordingly elevated while the counterweight 44 is at the same time lowered. When the latter reaches the end of its stroke the piston 40 contacts the lever 56 and piston 24 contacts lever 71 shifting the reversing linkage causing the pump unit 46 to deliver oil in the opposite direction. Thus the piston 24 is lowered and the piston 40 elevated, this reciprocation of the two pistons in opposite directions continuing as long as the handle 70 remains in the running position.

When it is desired to operate the tail pump 72 in synchronism with the movements of the work piston 24, the shut-off cock 110 is closed, as shown in the drawing, so that on the first upward stroke of piston 24, the oil discharged from the lower end of counterbalance cylinder 30 drives the piston 94 to the left in Figure 1. It will be noted that the check valve 102 prevents flow from port 98 to port 106.

When the piston 94 reaches the left-hand end of its stroke it passes beyond the port 104 and thus opens a free path for flow from the righthand side of piston 94 through check valve 100 to port 96 and thus into the lefthand portion of pipe 52. Accordingly the displacement of the piston 94 may be considerably less than that of either piston 24 or piston 40, the provision of the check valves 100 and 102 insuring that the piston 94 will be driven through its full stroke at each stroke of the work piston. During the downward movement of piston 24 the action at cylinder 92 is similar to that described but in the opposite direction, check valve 100 preventing reverse flow around the piston 94 at the start of the stroke and the check valve 102 permitting by-passing to occur after piston 94 has completed its stroke. When it is desired to discontinue operation of the tail pump while continuing operation of the work piston 24, the by-pass 110 may be opened thus permitting free flow between the two sections of pipe 52 without actuating piston 94.

While the form of embodiment of the invention as herein disclosed constitutes a preferred form, it is to be understood that other forms might be

adopted, all coming within the scope of the claims which follow.

What is claimed is as follows:

1. In a sucker rod type pumping system for oil wells having a hydraulically actuated well pump actuator including a work cylinder and piston assembly for reciprocating the sucker rod, a counterbalance cylinder and piston assembly reciprocable in timed relation to the movements of the sucker rod, and a hydraulic circuit including a pressure fluid supplying means connecting said cylinders, the combination of a tail pump having a reciprocable operating member, and a cylinder and piston connected in series in said circuit for operating said member.

2. In a sucker rod type pumping system for oil wells having a hydraulically actuated well pump actuator including a work cylinder and piston assembly for reciprocating the sucker rod, a counterbalance cylinder and piston assembly reciprocable in timed relation to the movements of the sucker rod, and a hydraulic circuit including a pressure fluid supplying means connecting said cylinders, the combination of a tail pump having a reciprocable operating member, a cylinder and piston connected in series in said circuit for operating said member, said last named cylinder and piston having a smaller displacement than that of the work cylinder, and means rendered effective at the completion of a stroke of the tail pump to form a by-pass across the last-mentioned piston.

3. In a sucker rod type pumping system for oil wells having a hydraulically actuated well pump actuator including a work cylinder and piston assembly for reciprocating the sucker rod, a counterbalance cylinder and piston assembly reciprocable in timed relation to the movements of the sucker rod, and a hydraulic circuit including a pressure fluid supplying means connecting said cylinders, the combination of a tail pump having a reciprocable operating member, a cylinder and piston connected in series in said circuit for operating said member, said last named cylinder and piston having a smaller displacement than that of the work cylinder, and means rendered effective at the completion of a stroke of the tail pump in each direction to form a bypass across the last-mentioned piston.

4. In a sucker rod type pumping system for oil wells having a hydraulically actuated well pump actuator including a work cylinder and piston assembly for reciprocating the sucker rod, a counterbalance cylinder and piston assembly reciprocable in timed relation to the movements of the sucker rod, and a hydraulic circuit including a pressure fluid supplying means connecting said cylinders, the combination of a tail pump having a reciprocable operating member, a cylinder and piston connected in series in said circuit for operating said member, means forming a bypass across the last-mentioned piston, and a valve for selectively closing or opening said bypass to render the tail pump selectively effective or ineffective.

5. In a sucker rod type pumping system for oil wells having a hydraulically actuated well pump actuator including a work cylinder and piston assembly for reciprocating the sucker rod, a counterbalance cylinder and piston assembly reciprocable in timed relation to the movements of the sucker rod, and a hydraulic circuit including a pressure fluid supplying means connecting said cylinders, the combination of a tail pump having a reciprocable operating member, a cylinder

and piston connected in series in said circuit for operating said member, means forming a bypass across the last-mentioned piston, and a manually operable valve for selectively closing or opening said bypass to render the tail pump selectively effective or ineffective.

6. In a sucker rod type pumping system for oil wells having a hydraulically actuated well pump actuator including a work cylinder and piston assembly for reciprocating the sucker rod, a counterbalance cylinder and piston assembly reciprocable in timed relation to the movements of the sucker rod, and a hydraulic circuit including a pressure fluid supplying means connecting said cylinders, the combination of a tail pump having a reciprocable operating member, a cylinder and piston connected in series in said circuit for operating said member, said last named cylinder and piston having a smaller displacement than that of the work cylinder, means rendered effective at the completion of a stroke of the tail pump to form a bypass across the last-mentioned piston, and check valve means for closing the bypass to flow in the direction to produce a return stroke of the tail pump.

7. In a sucker rod type pumping system for oil wells having a hydraulically actuated well pump actuator including a work cylinder and piston assembly for reciprocating the sucker rod, a counterbalance cylinder and piston assembly reciprocable in timed relation to the movements of the sucker rod, and a hydraulic circuit including a pressure fluid supplying means connecting said cylinders, the combination of a tail pump having a reciprocable operating member, and a cylinder and piston connected in series between said work and counterbalance cylinders for operating said member.

8. In a sucker rod type pumping system for oil wells having a hydraulically actuated well pump actuator including a work cylinder and piston assembly for reciprocating the sucker rod, a counterbalance cylinder and piston assembly reciprocable in timed relation to the movements of the sucker rod, and a hydraulic circuit including a pressure fluid supplying means connecting said cylinders, the combination of a tail pump having a reciprocable operating member, a cylinder and piston connected in series between said work and counterbalance cylinders for operating said member, said last named cylinder and piston having a smaller displacement than that of the work cylinder, and means rendered effective at the completion of a stroke of the tail pump to form a bypass across the last-mentioned piston.
9. In a sucker rod type pumping system for oil wells having a hydraulically actuated well pump actuator including a work cylinder and piston assembly for reciprocating the sucker rod, a counterbalance cylinder and piston assembly reciprocable in timed relation to the movements of the sucker rod, and a hydraulic circuit including a pressure fluid supplying means connecting said cylinders, the combination of a tail pump having a reciprocable operating member, a cylinder and piston connected in series between said work and counterbalance cylinders for operating said member, means forming a bypass across the last-mentioned piston, and a valve for selectively closing or opening said bypass to render the tail pump selectively effective or ineffective.
